(57) **CLAIM**

The ornamental design for an apparatus for carrying suspended items, as shown and described.

DESCRIPTION

FIG. 1 is a perspective view of the apparatus for carrying suspended items in accordance with an embodiment of the present invention.

FIG. 2 is a front view of the apparatus for carrying suspended items of FIG. 1.

FIG. 3 is a rear view of the apparatus for carrying suspended items of FIG. 1; and,

FIG. 4 is a perspective environmental view showing a shoulder strap attached to the apparatus of FIG. 1 for purposes of hands-free carrying of bags that may be suspended from the apparatus.

The broken line showing of environmental structure is for purposes of illustrating the claimed design in condition of use. The broken lines and structure they depict form no part of the claimed design.

1 Claim, 4 Drawing Sheets
